UNITED STATES PATENT OFFICE.

WILLIAM H. WILD, OF VALATIE, NEW YORK.

WHEEL-RAKE.

SPECIFICATION forming part of Letters Patent No. 363,034, dated May 17, 1887.

Application filed February 18, 1886. Serial No. 192,431. (No model.)

To all whom it may concern:

Be it known that I, WILLIAM H. WILD, a resident of Valatie, in the county of Columbia and State of New York, have invented certain new and useful Improvements in Wheel-Rakes; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in wheel-rakes, the object of which is fully set forth in the following description; and it consists in the novel construction and combination of parts, hereinafter described, and pointed out in the claims.

Figure 1 of the drawings is a plan view of my improved rake. Fig. 2 is a cross-sectional view showing dumping mechanism. Fig. 3 is a cross-sectional view showing the locking device and mechanism for operating the teeth-clearer. Fig. 4 is a vertical cross-section of the driving ratchet and pawl, taken at broken line xx in Fig. 1. Fig. 5 is a front view of link a^2 detached. Fig. 6 is an enlarged view of nut, spring, and pawl.

The axle A is provided with the actuating traction-wheels W , and supports the rake and operating mechanism, including thills F , cross-bars E , seat S , treadle T , head H , provided with teeth t , arms f , for supporting the operating mechanism for clearing the teeth, and dumping-ratchet D .

The dumping-ratchet is fixed to the axle and turns with it, and acts upon the rake through the pawl d , centrally pivoted upon arm a , which is pivoted at one end upon the teeth-supporting head and at the other end to a system of links and levers, a^2 , a^3 , and a^4 , which connect it with the operating-treadle T , pivoted upon the cross bars or slats b .

When the treadle is depressed, the link a^4 , acting through lever a^3 and link a^2 , depresses the pawl-supporting end of arm a , which causes the front one of the beveled ends of the pawl to be thrown up and the rear one down,

so as to engage with one of the ratchet-teeth, which carries the head H along with it until the forward point of the pawl, occupying the position on the ratchet shown by dotted lines, 55 strikes the stop e , which forces the point out from the ratchet and causes the pawl to perform a half-revolution on its pivot, reversing its ends, thereby releasing the head, the spring S' , secured at one end to arm a' and at the other 60 end to the pawl-supporting arm, acting to lift the pawl clear from the ratchet-teeth. The pawl being centrally pivoted, it matters not which of the like ends engages the ratchet, nor what its position is when the treadle is de- 65 pressed. If the pawl happens to be in the position shown in Fig. 2, the first tooth of the ratchet which strikes the lower end of the pawl will force the other end into immediate engagement with the next tooth. 70

The link a^2 is slotted, as shown in Fig. 5, which permits it to slide down upon the end of lever a^3 between its retaining-pins a^5 a^6 . I also provide a hooked arm, h , attached to the rake-head and pivoted upon the axle, 75 which not only acts to support the head, but is adapted to engage with the hook k , pivoted to the frame or slat b , to hold the rake-teeth in their proper position upon the ground.

When the treadle is depressed to dump the 8c rake, the link k' , connecting the heel of the treadle with the pivoted hook, lifts the hook from engagement with hook h , which releases the rake-head at the same time it is brought under the influence of the dumping-ratchet. 85 The stop e' , attached to hook h , serves to prevent the rake head and teeth from falling too far when released from the dumper, the end of arm h striking the stop and arresting its further progress. Hook k is forced down into 90 engagement with hook h by the spring k' .

The object of the bar C is to clear the hay from the teeth of the rake when dumped.

The teeth are all loosely secured to the bar C , as by the staples G , within which the teeth 95 are free to slide. The bar is supported by one end of the levers g , pivoted upon the braces f , fixed upon the frame or thills F and projecting to the rearward of the axle, as shown in Fig. 3. The other ends of levers g are connected by the pivoted links l' with the rake-head, as shown. It is obvious therefore that 100

when the head is thrown forward by the dumping-ratchet it acts, through link l and levers g , to quickly depress the clearing-bar. At the same time the rake-teeth are elevated, 5 thus forcing from the teeth any adhering substance.

When turning around or at any angle with the rake, it is well known that one wheel travels faster than the other, and various kinds of 10 pawl-and-ratchet mechanisms have been heretofore adopted to permit the wheels to revolve backward upon the axle without imparting to it a rotary motion. The mechanism which I employ for this purpose is shown in Fig. 4.

15 K is the ratchet, which is fixed upon the axle A, and J is the pawl adapted to engage with the ratchet. The pawl consists of a pin beveled at its lower engaging end, as shown, and adapted to slide loosely in a socket in the 20 rim or barrel R, surrounding and inclosing the ratchet. The barrel is firmly secured to the wheel-hub or forms a part of it. The mouth of the socket is interiorly threaded and closed by a correspondingly-threaded nut, N. The 25 pawl has a small guiding-spur, n, projecting up into a coil-spring, m, which bears upon the pawl at one end and the nut at the other. The action of the spring is to keep the pawl in engagement with the teeth of the ratchet. 30 When the rake is advancing, the pawl engages with the ratchet-teeth and forces the axle to rotate. When the revolution of the wheels or axle is reversed, the pawl slides over the teeth, rising in its socket and over- 35 coming the force of the spring. The pawl and its socket are slightly tapered, the upper end of the pawl being slightly larger than the lower end of the socket, so that the pawl cannot drop too far out of its socket as it slides radially. 40 Such a form of construction, by entirely inclosing the pawl and ratchet, protects them from the dust and hay, and prevents the intervention of foreign substances which might interfere with their free operation.

To gain access to the pawl and co-operating 45 parts, it is only necessary to unscrew and remove the threaded nut N. The entire mechanism is compact, and can be cheaply constructed in a durable manner.

By making the rake-head curved in form, as 50 I have shown in Fig. 1, I am able to have the rake-teeth all of the same length, and at the same time have the teeth adjacent to the rake-wheels in advance of the intermediate teeth, which tends to keep the hay away from the 55 wheels by throwing it toward the center of the rake.

What I claim as new, and desire to secure by Letters Patent, is—

1. In a horse-rake, the combination, with 60 the rake-head axle and a treadle and lever, a^3 , connected by a link, of a pivoted link, a^2 , slotted to slide over the lever a^3 , and a spring-supported link, a , one end pivoted to rake-head, whereby a pawl, d , having its middle 65 pivoted to said link a , may be carried down to gear with a ratchet-wheel, D, in the manner and for the purpose described.

2. In a wheel-rake, the combination of axle 70 A, ratchet-wheel D, fixed upon the axle, pawl d , arm a , rake-head H, treadle T, fulcrumed upon the rake-frame, and connecting-links a^2 , a^3 , and a^4 , substantially as described, and for the purposes set forth.

3. The combination, in a wheel-rake, with 75 an axle and rake-head, of the hook-arm h , pivoted on the axle, a pivoted hook, k , having stop e' , a link, k' , and a spring, k^2 , as and for the purpose specified.

In testimony whereof I have hereunto set my 80 hand this 4th day of January, 1886.

WILLIAM H. WILD.
